UNITED STATES PATENT OFFICE.

CHARLES A. HANSON, OF DONOVAN, ILLINOIS.

WIRE-WINDING MACHINE.

1,142,035.

Specification of Letters Patent.

Patented June 8, 1915.

Application filed April 5, 1913. Serial No. 759,088.

To all whom it may concern:

Be it known that I, CHARLES A. HANSON, a citizen of the United States, residing at Donovan, in the county of Iroquois and State of Illinois, have invented certain new and useful Improvements in Wire-Winding Machines, of which the following is a specification.

This invention relates to winding machines or reels, and more especially to that class thereof adapted for reels of wire, either for unwinding or winding, and which may be transported from place to place as required, and it has for one of its objects 15 the provision of an improved mechanism for connecting and disconnecting the main arbor of the reel with a member adapted to be manually rotated for winding purposes.

A further object of the invention resides 20 in the provision of an improved adjustable guide for controlling the wire during the winding and unwinding period, this guide being adapted to be swung out of the way to permit a fresh reel to be inserted into the 25 frame of the machine.

Further objects of the invention will hereinafter appear and be particularly defined in the claim.

The invention has been clearly illustrated 30 in the accompanying drawing, in which similar characters denote similar parts, and in which—

Figure 1 is a top view of a wire-winding machine embodying my invention. Fig. 2 35 is a side view thereof. Fig. 3 is a vertical section substantially on line 3, 3, of Fig. 2. Fig. 4 is a rear view of the wire guide. Fig. 5 shows one end view of the reel fitted for use in the machine. Fig. 6 is a face view of 40 the reel-controlling member.

Referring to the drawing, 10, 10' denote 45 a pair of side frames upon which the reel controlling members are mounted, and which are supported by wheels 11, 11' journaled on trunnions 12, 12' which are rigidly held 50 in brackets 13, 13' secured by the side frames, 10, 10', respectively, as is clearly shown in Fig. 1.

In order to avoid interference with the 55 wire reel, the side frames 10 and 10' are connected integrally by a drop member or strap 14 which also acts as a spacer member to keep the brackets 13, 13' properly spaced to receive between them the wire reel and its driving mechanism. The latter comprises preferably a sprocket wheel 15, the spindle

16 of which is journaled in the bracket 13' above mentioned, and the hub 15' of which is provided with a polygonal recess 17 to receive a correspondingly shaped driver 18 secured to the reel-carrying shaft 19. The other end of this shaft is journaled in the bracket 13 which is provided with a vertical slot 20 permitting the insertion of the shaft-end into place, where it may be held 60 by a cotter pin or similar device 21 extending across the top of the same.

The driver 18 is provided with a pair of clutch fingers 22 adapted to straddle one of the reel bars, such as 23, in the manner 70 shown in Fig. 3, so that after the pin 21 has been removed, that end of the shaft 19 can be raised out of the bracket 13, through the slot 20, and the entire shaft 19, together with the reel, can then be readily slid side- 75 wise or longitudinally of the shaft to bring the driver 18 out of the recess 17.

It should be noted that in the present instance the reel shaft 19 is disposed directly in a vertical line above the wheel trunnions 80 12, 12', so that by this manner of support, the wheels will take the entire load of the reel and the wire contained thereon, without laying any hardship onto the operator of the machine, other than that of manipulating the overhanging side bars 10, 10', the free ends of which are connected by a hand bar 24, whereby the machine in its entirety 85 may be transported from place to place.

The sprocket wheel 15 is connected by a 90 chain 25 with a sprocket 26 secured upon a transverse shaft 27 which is journaled in bearings 28, 28' and has a crank 29 whereby the rotation of the reel in either direction is controlled.

A brace 30 extending from one side frame to the other may serve to hold the latter in substantially horizontal position so that the crank 29 may be within easy reach of the operator.

Pivoted at 31, 31' on the side frames 10, 10', respectively, are the ends of a U-shaped bar 32 which constitutes the principal holding member for a wire guide comprising a pair of L-shaped members 33, 34 which are 105 capable of adjustment relatively to each other on the bar 32, substantially in the manner shown in Fig. 4, to provide for guiding the wire onto spools of different lengths, the members 33, 34, having flattened portions 33', 34' respectively adapted to be clamped against the bar 32 by handle nuts 110.

35, 36 attached to bolts 37, 38 which are adapted to be adjusted in slots 39, 40 of the bar 32. The other ends of the wire guide members 33, 34, may be connected as shown 5 partly in section in Fig. 4, which illustrates the member 33 as having a reduced portion 33" adapted to telescope into the tubular portion 34" of the other member 34. It 10 should be noted that a guide wheel indicated by dot-and-dash lines 41 may be provided for rotation as well as longitudinal movement on the guides 33, 34.

When it is desired to unload or load the machine, the frame 32 may be swung entirely 15 out of the way into the position shown by dot-and-dash lines 32^a indicated in Fig. 2, it being understood that under ordinary conditions the brackets 13, 13' serve as supports upon which the side members of the 20 frame 32 can rest.

Changes may be made in the general organization as well as in the particular construction of some of the elements of my

improved machine without departing from the spirit of the invention, especially in the 25 manner of controlling the rotation of the reel, as well as in the formation of the clutch member whereby the reel is rotatably connected with its supporting shaft.

I claim:—

In a machine of the character described, the combination with a reel holder, and a frame supporting the same, of a wire guide consisting of a pair of side-members facing each other and having their horizontal portions telescoping one into the other, and means for adjustably positioning the vertical portions of said side-members to the frame.

In testimony whereof I affix my signature in presence of two witnesses.

CHARLES A. HANSON.

Witnesses:

F. S. JOHNSON,
C. J. JOHNSON.
